United States Patent Office.

CHARLES W. CAHOON, OF PORTLAND, MAINE.

Letters Patent No. 94,396, dated August 31, 1869.

IMPROVEMENT IN LOCOMOTIVE-ENGINES.

The Schedule referred to in these Letters Patent and making part of the same

To all whom it may concern:

Be it known that I, CHARLES W. CAHOON, of Portland, in the county of Cumberland, and State of Maine, have invented a new and useful Improvement in Locomotives; and I hereby declare the following to be a full, clear, and exact description thereof, which will enable others to make and use my invention, reference being had to the accompanying drawings, forming part of this specification, in which—

Figure 1 is a top plan of the running-gear and engines.

Figure 2 is a side elevation of boiler and engines, and a sectional elevation of the running-gear.

My invention consists—

First, in an improved device for facilitating the propulsion of cars, &c., and

Second, in an improved method of communicating motion to the driving-wheels.

In the operation of street-car locomotives, where steep grades are frequently encountered, it is of great importance that a large amount of tractive power should be ready at hand to be brought into use when needed, and for this purpose, I have attached to the locomotive an adjustable friction driving-wheel.

It is also desirable in street-locomotives, and especially in the locomotive patented by me, November 5, 1867, that they may be capable of being operated with a low pressure of steam, and at the same time not have inconveniently large engines, and also that the engines may be placed perpendicularly, or nearly so, at one end of the locomotive, when the crank-shaft for operating the driving-wheels is at the other end; and to obtain this result, I place a vibratable arm in the connecting-rod between the engine and the crank-shaft of the driving-wheels, so as to change the line of motion of the connecting-rod, and also to obtain leverage thereby.

The locomotive presented in the drawing is of that class patented by me, November 5, 1867, and is intended to be operated without fire upon the same, the water for making the steam being heated at a stationary boiler, and transferred therefrom to the locomotive.

A represents the hot-water tank.

B, the frame-work of the platform on which rests the tank, engines, &c.

C is the crank-shaft which operates the main driving-wheels D D, and likewise the adjustable friction driving-wheels E E.

These wheels E are set in a vibratable frame, F, which is pivoted to the crank-shaft C. They are made of vulcanized rubber, and are intended to act upon the track between the rails, being operated by a gear-wheel, 1, attached to their shaft, and connecting with a gear-wheel, 2, on the crank-shaft.

b' represent spurs in the periphery, which are held

therein by a transverse rod, put through the side and through the inner part of the spur, within the wheel.

These spurs may or may not be used, depending upon the weight of the locomotive and the load to be hauled.

G is a screw passing through a loose nut in a cross-bar in the bottom frame B, with the lower end jointed loosely in the frame F. The upper end has a handle attached at a convenient height to be easily operated.

The wheels E E are brought into action by simply turning down the screw G until they come in contact with the ground. Turning it up, of course takes them out of action.

H is the vibratable arm in the connecting-rod, and is pivoted to a cross-bar in the frame B, the connecting-rod, in its vertical action, being attached to one side of this arm, at a, and in its horizontal action to the other side, at b, the side a being the longest, so as to produce leverage upon the driving-wheels.

3 is a gear-wheel on the shaft of the driving-wheels D D, and is connected with the gear-wheel 2 on the crank-shaft.

c is the engine.

d, the valve-rod.

e, a tank in front of the engine, to receive the exhaust steam, and to let it off gradually, to prevent noise.

f, pipes for letting off the condensed water from the engines, which pipes also lead into the tank e.

g is a pipe to let off the condensed water.

h is the exhaust-pipe.

i, a pipe to carry steam from the reservoir-tank to the engines.

j is a pipe to let off steam and air while filling the reservoir with hot water from the stationary boiler.

k, the filling-pipe.

l, the discharging-pipe.

The driving-wheels D D are constructed with cushioned, or partly-elastic peripheries, in accordance with a prior application for patent by me.

The brakes, when the wheels are thus constructed, may be made to operate upon the sides of the wheels, instead of upon their peripheries, as usual.

What I claim as my invention, and desire to secure by Letters Patent, is—

1. The adjustable friction driving-wheels connected to the locomotive, as set forth, and capable of an intermittent or continuous operation, as herein described.

2. The cylinder c, bell-crank a, and connecting-rods with crank-shaft C, driving-wheels D, and supplementary adjustable driving-wheels E E, when constructed and arranged as described.

CHARLES W. CAHOON.
